(57) **CLAIM**

The ornamental design for a pressing tool, as shown and described.

DESCRIPTION

FIG. 1 is a front right perspective view of a pressing tool. FIG. 2 is a right side view of the pressing tool of FIG. 1. FIG. 3 is a left side view of the pressing tool of FIG. 1. FIG. 4 is a top view of the pressing tool of FIG. 1. FIG. 5 is a bottom view of the pressing tool of FIG. 1. FIG. 6 is a rear view of the pressing tool of FIG. 1; and, FIG. 7 is a front view of the pressing tool of FIG. 1. The evenly spaced broken lines and unshaded areas depict portions of the pressing tool that form no part of the claimed design. The dash-dot-dash broken lines depict environmental subject matter that forms no part of the claimed design.

1 Claim, 6 Drawing Sheets
